US00D962837S

(12) **United States Design Patent** (10) Patent No.: **US D962,837 S**
(45) Date of Patent: ** Sep. 6, 2022

(54) **SET OF VEHICLE WINDOWS**

(71) Applicant: **Canoo Technologies Inc.**, Torrance, CA (US)

(72) Inventors: **Richard Kim**, Los Angeles, CA (US); **Brian Oh**, Rancho Palos Verdes, CA (US); **Jackson E. Luttig**, Rancho Palos Verdes, CA (US); **Brian Spencer**, Lakewood, CA (US); **Sagar Shrivastava**, San Pedro, CA (US); **Calvin Liu**, Torrance, CA (US)

(73) Assignee: **Canoo Technologies Inc.**, Torrance, CA (US)

(**) Term: **15 Years**

(21) Appl. No.: **29/804,204**

(22) Filed: **Aug. 18, 2021**

Related U.S. Application Data

(62) Division of application No. 29/706,601, filed on Sep. 20, 2019, now Pat. No. Des. 941,203.

(51) **LOC (13) Cl.** **12-16**

(52) **U.S. Cl.** USPC **D12/183**

(57) **CLAIM**

The ornamental design for a set of vehicle windows, as shown and described.

DESCRIPTION

FIG. 1 is a perspective view of a set of vehicle windows, according to an embodiment of the invention.

FIG. 2 is a top view thereof.

FIG. 3 is a side view thereof.

FIG. 4 is a perspective view of a vehicle including the set of vehicle windows.

FIG. 5 is a side view thereof; and,

FIG. 6 is a top view thereof.

Mirror images of the set of vehicle windows as shown in the figures are within the scope of the claimed design.

The broken lines in the figures illustrate environmental features and do not form part of the claimed design.

1 Claim, 6 Drawing Sheets
